(57) **CLAIM**

The ornamental design for a pocket for pants' legs, substantially as shown and described.

DESCRIPTION

FIG. 1 is a first embodiment of the pocket for pants' legs showing our new design;

FIG. 2 is a second embodiment of the pocket for pants' legs; FIG. 3 is a third embodiment of the pocket for pants' legs; and,

FIG. 4 is a fourth embodiment of the pocket for pants' legs. The dot-dash broken line immediately adjacent the shaded areas represent the bounds of the claimed design, while all other broken lines are included for the purpose of illustrating the unclaimed portion of the pants and such broken lines forming no part of the claimed design.
